UNITED STATES PATENT OFFICE.

ARTHUR JAMES JACKSON, OF TORONTO, CANADA.

DESIGN FOR A BACK-PLATE FOR SUSPENDERS.

SPECIFICATION forming part of Design No. 30,718, dated May 9, 1899.

Application filed April 8, 1899. Serial No. 712,328. Term of patent 7 years.

To all whom it may concern:

Be it known that I, ARTHUR JAMES JACKSON, a subject of Her Majesty the Queen of Great Britain, residing in the city of Toronto, in the county of York, in the Province of Ontario, Canada, have invented and produced a new and original Design for a Back Connecting-Plate for Suspenders, of which the following is a specification, reference being had to the accompanying drawings, forming part thereof.

Figure 1 is a face view of the plate. Fig. 2 is a section.

As shown in the drawings, the leading or ; material feature of my design consists of a

double plate A, substantially heart-shaped in form, with a loop B at the bottom, tabs C at the top provided with loops D, and rivets E, located centrally at each side of the arc-shaped tops.

Having described my invention, what I claim as new, and desire to secure by Letters Patent, is—

The design for a back-plate for suspenders herein shown and described.

ARTHUR JAMES JACKSON.
